COMBINED DESK CLOCK AND BAROMETER

Samuel J. Kaufman, New York, N. Y.

Application July 7, 1952, Serial No. 20,499

Term of patent 3½ years

(CL. D42—7)

To all whom it may concern:

Be it known that I, Samuel J. Kaufman, a citizen of the United States, residing at New York city, in the county and State of New York, have invented a new, original, and ornamental Design for a Combined Desk Clock and Barometer, of which the following is a specification, reference being had to the accompanying drawing, forming a part thereof.

Fig. 1 is a top perspective view of the combined desk clock and barometer, showing my new design.

Fig. 2 is an end view thereof, taken from the left of Fig. 1.

Fig. 3 is a sectional view taken on line 3—3 of Fig. 1.

I claim:

The ornamental design for a combined desk clock and barometer, substantially as shown.

S. J. KAUFMAN.
